UNITED STATES PATENT OFFICE.

NATHANIEL G. BEDDIDGE, OF BOISE, IDAHO.

AUTOMOBILE-WASHER.

1,192,736.

Specification of Letters Patent. Patented July 25, 1916.

Application filed March 25, 1916. Serial No. 86,649.

To all whom it may concern:

Be it known that I, NATHANIEL G. BEDDIDGE, a citizen of the United States, residing at Boise, in the county of Ada and State of Idaho, have invented certain new and useful Improvements in Automobile-Washers; and I do hereby declare the following to be a full, clear, and exact description of the invention, such as will enable others skilled in the art to which it appertains to make and use the same.

The invention relates to improvements in washing devices.

The object of the present invention is to improve the construction of washing devices and to provide a simple, practical and inexpensive washing device designed for cleaning varnished and similar surfaces of automobiles and various other vehicles and adapted to afford a continuous flow of water in conjunction with a mop cloth whereby such surfaces may be thoroughly and rapidly cleaned without liability of scrubbing or otherwise marring or damaging the finish of the surface.

A further object of the invention is to provide a cleaning device of this character adapted to permit the ready removal of the mop cloth element or member for washing the same or renewing such element should this become necessary.

With these and other objects in view the invention consists in the construction and novel combination and arrangement of parts hereinafter fully described, illustrated in the accompanying drawings and pointed out in the claim hereto appended, it being understood that various changes in the form, proportion and minor details of construction may be resorted to without departing from the spirit or sacrificing any of the advantages of the invention.

In the drawing Figure 1 is an elevation of an automobile washer constructed in accordance with this invention, Fig. 2 is a sectional view of the same, partly in elevation, Fig. 3 is a detail perspective view of the nozzle, Fig. 4 is a plan view of the mop cloth member.

Like numerals of reference designate corresponding parts in the several figures of the drawing.

In the accompanying drawing in which is illustrated the preferred embodiment of the invention, the automobile washer comprises in its construction, a substantially cylindri-

cal nozzle 1 provided with front and rear heads 2 and 3 which are extended beyond the curved walls of the cylinder or cylindrical nozzle to form projecting front and rear flanges 4 and 5 and an intervening annular groove 6 which is adapted to receive a mop cloth member 7. While the hollow nozzle is shown in cylindrical form, it may of course be varied in configuration as will be readily understood and the front wall is provided with a plurality of apertures 8 for the discharge of water. The rear wall is provided with a central opening 9 and connected to the rear wall at the said opening is a pipe connection 10 which is preferably in the form of an elbow coupling and which is provided at its outer end with interior screw threads 11 to enable it to be readily coupled to the end of an ordinary hose 12.

The mop cloth member consists of strands of cotton twine secured together by a flexible binding 13 of stout fabric such as canvas but any other desired material may of course be employed in the construction of the mop cloth member and the bound portion forms a body 14 which is bent in annular form around the cylindrical nozzle and is arranged in the groove 6 between the front and rear flanges 4 and 5 being secured in position by a fastening device consisting of a loop member and a locking lever 16. The loop member is provided with a plurality of slots 17 and the locking lever is pivotally mounted on an attaching plate 18 and is adapted to be passed through the slots 17 for detachably securing the ends of the mop cloth member together for retaining the mop cloth member on the nozzle. Any other form of catch or fastening device may be employed and as the particular construction of the catch or fastening device does not constitute a portion of the present invention further description thereof is deemed unnecessary.

The jet apertures 8 of the nozzle may be of any desired number and they simultaneously deliver streams or jets of water to the strands of the mop cloth element so that a continuous supply of water is applied to the surface being cleaned simultaneously with the mop cloth member. By this construction varnished and other highly polished surfaces may be rapidly and thoroughly cleaned without liability of the washing device scratching or otherwise marring the finish of such surfaces.

What is claimed is:—

A washing device of the class described including a hollow nozzle composed of front and rear heads and a connecting wall, the 5 heads being extended beyond the connecting wall to form spaced flanges and an intervening groove, said front wall being provided with jet apertures, a pipe connection extending from the rear wall of the nozzle 10 and having means for connecting it to a

water supply and a mop cloth member secured in the groove of the nozzle and extending in advance of the same so as to be supplied with water from the jet apertures.

In testimony whereof I affix my signature 15 in presence of two witnesses.

NATHANIEL G. BERRIDGE.
